2 SHEETS—SHEET 2.

UNITED STATES PATENT OFFICE.

ERNEST DIETZ, OF BUFFALO, NEW YORK, ASSIGNOR TO PEARL MANUFACTURING COMPANY, OF BUFFALO, NEW YORK, A CORPORATION OF NEW YORK.

LUBRICATOR.

No. 810,194.

Specification of Letters Patent.

Patented Jan. 16, 1906.

Application filed June 26, 1905. Serial No. 266,917.

To all whom it may concern:

Be it known that I, ERNEST DIETZ, a citizen of the United States, residing at Buffalo, in the county of Erie and State of New York, have invented a new and useful Improvement 5 in Lubricators, of which the following is a specification.

This invention relates to lubricators which are adapted to be operated by a movable 10 part of the machine to which the lubricator is applied, the same having particular relation to devices of this kind comprising a pair of pump-cylinders into one of which oil is drawn or supplied while the contents of the 15 other are being discharged, the two cylinders thus feeding oil alternately to the part to be lubricated.

The principal object of my invention is the construction of a continuous and uniform 20 feed-lubricator of this character which requires no manual reversal or resetting from time to time, but is absolutely automatic in action.

Further objects of the invention are to produce 25 a lubricator of this class which shall be simple and compact in construction and positive and reliable in operation and in which the valve mechanism is easy of access for repairing the same when necessary.

In the accompanying drawings, consisting 30 of two sheets, Figure 1 is a sectional side elevation of the lubricator, the plane of the sectional portion being in line 1 1, Fig. 3. Fig. 2 is a vertical longitudinal section taken centrally through the device. Fig. 3 is a horizontal section in line 3 3, Fig. 2. Fig. 4 is a transverse section in line 4 4, Fig. 3. Fig. 5 is an end view of the eccentric and cam-sleeve with the main shaft shown in cross-section.

Similar letters of reference indicate corresponding parts throughout the several views.

A indicates the base of the lubricator, which is preferably provided with a screw-socket 45 adapted to receive the threaded upper end of a supporting-post A', as shown in Figs. 1 and 2.

B B' are a pair of pump-cylinders mounted horizontally upon the raised end portions of 50 the base and arranged in line and so as to face each other. In the preferred construction shown in the drawings the cylinders are

supported by short posts b, cast integral therewith and resting upon the base, to which latter they are secured by vertical bolts b'. 55

C C' are the pistons or plungers of the pump - cylinders passing through suitable stuffing-boxes in the opposing ends of the cylinders and having their outer ends secured to opposite sides of a yoke D. The latter is reciprocated by an eccentric E, turning in the bearing-block D' of the yoke and secured to a transverse shaft F, arranged midway between the cylinders and supported by standards F' F'', rising from the base A. 60 This shaft is slowly rotated from a movable part of the machine to be lubricated by any suitable means. Preferably the ratchet mechanism shown in the drawings is used for this purpose, the same consisting of a ratchet-wheel G, secured to the projecting end of the shaft F, and a feed-pawl g, engaging therewith and carried by an oscillating disk or head H. This disk turns upon a comparatively large hub H', secured to the adjacent 70 standard F'', the disk having a marginal flange h, which overlaps a corresponding flange h' of the hub, as shown in Fig. 3. The disk is provided with a depending actuating arm or rod H'', adapted to be connected with 75 the valve-rod of a steam-engine or equivalent part by a rod. (Not shown in the drawings.) I is a suitable detent engaging with the ratchet-wheel G.

Each of the cylinders B B' is provided with 85 an inlet-port j and an outlet-port j', which ports connect the cylinder with inlet and outlet chambers J J', respectively, arranged on opposite sides of the cylinder and preferably cast in one piece therewith. The inlet-chambers of the cylinders are supplied from an oil-reservoir K, surmounting the cylinders and supported thereon by posts k, having passages k', through which the oil flows into said chambers, as best shown in Fig. 4. The 90 passage of the oil to and from the cylinders is controlled by valve mechanism of any suitable construction; but the mechanism shown in the drawings is preferably employed for this purpose. The same is constructed as 95 follows: l l indicate check-valves arranged in the inlet-chambers J for preventing return of the oil from said chambers and the cylinders into the oil-reservoir. These valves co-

operate with seats l' , arranged in the front portions of the corresponding chambers, and are closed by springs l^2 , applied to their stems and abutting at their front ends against the valve-heads and at their rear ends against removable plugs m , screwed into the rear ends of the cylinders. These plugs are provided with axial sockets m' , in which the stems of the inlet-valves l are guided. The inlet-valves are opened alternately by a cam n , secured to the main shaft F and acting upon the valves through thrust-rods n' , bearing at their ends against the valves and the faces of the cam and passing through suitable stuffing-boxes at the front ends of the inlet-chambers J . The inlet-valves and their stems are preferably provided with axial bores which receive the rear ends of said thrust-rods, as shown in Fig. 3, so that these rods serve as guides for the valves.

The outlet-chambers J' are provided with check-valves o for preventing the oil from returning from the same into the cylinders. These outlet-chambers and their check-valves are identical in construction with the inlet-chambers J and valves j , said outlet-valves being closed by springs o' and opened by thrust-rods o^2 , which are acted on by a cam o^3 similar to the cam n . These cams are arranged on diametrically opposite sides of the shaft F , and the relation of the two sets of thrust-rods $n' o^2$ to the cams is such that when the inlet-valve of one cylinder is open its outlet-valve is closed, and vice versa, while at the same time the valves of the other cylinder are in the reversed position, as shown in Fig. 3, so that in the operation of the lubricator one cylinder is being filled while the other is being emptied. As shown in the last-mentioned figure, the valve-operating cam $n o^3$ may be formed integral with the hub or sleeve which carries the piston-operating eccentric E .

Each of the outlet-chambers J' has a discharge passage or nipple p , Figs. 3 and 4, to which is connected a delivery-pipe p' , leading to the part to be lubricated. These pipes are provided with stop-cocks p^2 and connected by a by-pass or pipe p^3 , which joins the same between their stop-cocks and the outlet-chambers of the lubricator, said connecting-pipe having a stop-cock p^4 . By this arrangement upon opening the stop-cock p^4 and the cock p^2 of one of the delivery-pipes p' , as shown in Fig. 3, the oil from both cylinders is continuously delivered to the same part through one of the delivery-pipes, or, if desired, the lubricant may be delivered alternately to different parts by closing the stop-cock of the connecting-pipe p^3 and opening the cocks of both delivery-pipes p' .

The operation of the apparatus is as follows: The arm H^2 of the oscillating disk H being connected with a reciprocating mem-

ber of the machine to be lubricated, rotary motion in one direction is imparted to the main shaft F by the ratchet device hereinbefore described. Assuming the parts to occupy the positions shown in Fig. 3, the piston of the left-hand cylinder B has just completed its forcing stroke and the piston of the right-hand cylinder B' has just completed its suction-stroke, filling the latter with oil. The outlet-valve o of the left-hand cylinder and the inlet-valve l of the right-hand cylinder have been allowed to close by their opening-rods $n' o^2$ clearing the abrupt ends of the cams $n o^3$, while the inlet-valve of the left-hand cylinder and the outlet-valve of the right-hand one are about to be opened by said cams. During the next suction-stroke of the left-hand piston and the corresponding forcing stroke of the right-hand piston the right outlet-valve o is opened by the cam o^3 and the oil is expelled from the right-hand cylinder into and through the outlet-chamber J' thereof and thence through the connecting-pipe p^3 and the left-hand delivery-pipe p' , assuming the stop-cocks of these pipes to be in the position shown in Fig. 3. At the same time the left inlet-valve l is opened by the cam n and another charge of oil is drawn into the left-hand cylinder in front of its receding piston. When the pistons reach the opposite extremity of their stroke, they are moved in the reverse direction by the action of the rotary eccentric E and the yoke D , causing the oil to be expelled from the left-hand cylinder and its outlet-chamber directly into the corresponding delivery-pipe p' and another charge to be simultaneously drawn into or supplied to the right-hand cylinder. In this manner the oil is alternately expelled from the cylinders, the one beginning to deliver the same to the part to be lubricated immediately after the other becomes empty and continuing the feeding operation until its contents are expelled, when the other cylinder repeats the operation, and so on, as long as the lubricator is actuated and its reservoir kept supplied with oil. As the two pistons are positively and automatically reversed at the end of each stroke, the action of the alternately-operating pumps is wholly automatic, and they together effect a practically continuous feed of oil to the part to be lubricated when their outlet-chambers are both connected to a common delivery-pipe, as hereinbefore described. No interruptions of the feed can therefore take place, such as are liable to occur through neglect or otherwise, where the reversal or alternate action of the pump-cylinders must be effected by hand.

The cams $n o^3$ and thrust-rods $n' o^2$ constitute positive opening means for the inlet and outlet valves, and the closing-springs $l^2 o'$ of the valves can therefore be made stiffer or of

greater resistance than is possible where the valves are opened by atmospheric pressure, thus insuring a tight closure of the valves, preventing leakage past the same, and increasing the efficiency of the lubricator.

While but a single pair of pump-cylinders and pistons is herein shown and described, the same can obviously be duplicated or multiplied, according to the number of different parts to be oiled by the same lubricator.

My improved lubricator is especially desirable for oiling the steam-cylinders and other parts of locomotives, but may be used for lubricating various other machines.

Upon removing the screw-plugs in the rear ends of the valve-chambers the valves are accessible for repairing or removing them, and their seats can be reground, if necessary. By making the rods n° o° separate from the valves the latter can be removed from their chambers without disturbing the packing or stuffing-boxes of the same.

I claim as my invention—

1. In a lubricator, the combination of a cylinder containing a piston and having inlet and outlet chambers, valves arranged in said chambers and controlling the passages between the same and the cylinder, springs for closing said valves, and positive opening means for the valves constructed to operate the same alternately, substantially as set forth.

2. In a lubricator, the combination of a cylinder containing a piston and having inlet and outlet chambers connected therewith, valves arranged in said chambers and controlling the passages between the same and the cylinder, springs for closing said valves, and rotary cams arranged to alternately open said valves, substantially as set forth.

3. In a lubricator, the combination of a cylinder containing a piston and having inlet and outlet chambers connected therewith, valves arranged in said chambers and controlling the passages between the same and the cylinder, springs for closing said valves, a rotary shaft extending across the cylinder, cams mounted on said shaft, and thrust-rods interposed between said cams and said valves, substantially as set forth.

4. In a lubricator, the combination of a cylinder containing a piston and having inlet and outlet chambers connected therewith, and each provided in its rear end with a removable plug, valves arranged in said chambers and controlling the passages between the same and the cylinder, springs for closing said valves, and rotary cams arranged to alternately open the valves, substantially as set forth.

5. In a lubricator, the combination of a pair of opposing cylinders each provided with an inlet and an outlet chamber and inlet and outlet ports connecting each cylin-

der with its corresponding chambers, check-valves arranged in said chambers and controlling said inlet and outlet ports, pistons arranged in the cylinders, and an actuating-shaft arranged between the cylinders and carrying an eccentric which reciprocates said pistons and cams which operate said valves, substantially as set forth.

6. In a lubricator, the combination of a pair of opposing cylinders each provided on opposite sides with an inlet and an outlet chamber, inlet and outlet ports connecting each cylinder with its corresponding chambers, check-valves arranged in said chambers and controlling said inlet and outlet ports, springs for closing said valves, pistons arranged in said cylinders, and an actuating-shaft arranged between the cylinders and carrying an eccentric which reciprocates said pistons and cams which open said valves, substantially as set forth.

7. In a lubricator, the combination of a pair of opposing cylinders each provided on opposite sides with an inlet and an outlet chamber, corresponding chambers of the cylinders being arranged opposite or in line with each other, inlet and outlet ports connecting each cylinder with its corresponding chambers, check-valves arranged in said chambers and controlling said ports, springs for closing said valves, a shaft arranged transversely between said cylinders and provided in line with said inlet and outlet chambers with oppositely-arranged cams, the one adapted to open the inlet-valves alternately and the other to open the outlet-valves alternately, pistons arranged in said cylinders and means for actuating the pistons, substantially as set forth.

8. In a lubricator, the combination of a pair of opposing cylinders each provided on opposite sides with an inlet and an outlet chamber, inlet and outlet ports connecting each cylinder with its corresponding chambers, check-valves arranged in said chambers and controlling said inlet and outlet ports, springs for closing said valves, pistons arranged in said cylinders, a yoke connecting the pistons, an actuating-shaft arranged transversely between the cylinders and carrying an eccentric which reciprocates said yoke, oppositely-arranged cams mounted on said shaft in line with the check-valves of said inlet and outlet chambers, respectively, and thrust-rods interposed between said cams and said check-valves, substantially as set forth.

Witness my hand this 16th day of June, 1905.

ERNEST DIETZ.
